W. PACHECO,
SINGLE DELIVERY MATCH BOX,
APPLICATION FILED APR. 22, 1914.

1,135,133.

Patented Apr. 13, 1915.

UNITED STATES PATENT OFFICE.

WILLIAM PACHECO, OF CHICAGO, ILLINOIS.

SINGLE-DELIVERY MATCH-BOX.

1,135,133.

Specification of Letters Patent. Patented Apr. 13, 1915.

Application filed April 22, 1914. Serial No. 833,711.

To all whom it may concern:

Be it known that I, WILLIAM PACHECO, a citizen of the United States, residing at Chicago, in the county of Cook, State of Illinois, have invented certain new and useful Improvements in Single-Delivery Match-Boxes; and I do hereby declare the following to be a full, clear, and exact description of the invention, such as will enable others skilled in the art to which it appertains to make and use the same.

This invention relates to improvements in match boxes and particularly to match boxes for delivering a single match at a time.

One object of the invention is to provide a match box for delivering a single match in which crowding of the matches on the delivering member is prevented so that only one match finally is delivered from the box.

Another object is to provide a match box which will present a single match in a position to be conveniently grasped.

Other objects and advantages will be apparent from the following description, when taken in connection with the accompanying drawings.

In the drawings: Figure 1 is a vertical longitudinal sectional view through the box showing the parts in normal position. Fig. 2 is a vertical longitudinal sectional view through the upper portion of the box showing the operation of the means for brushing off all but the match that is to be delivered. Fig. 3 is a vertical sectional detail showing the manner in which the brushing device is pushed out of the way of the match delivering member. Fig. 4 is a vertical transverse sectional view showing the manner in which the match is tilted to stand in a vertical position for convenient grasping thereof.

Referring particularly to the accompanying drawing, 10 represents the stand in which is telescoped to slide vertically the match receptacle 11. The bottom of the stand is provided with a suitable flange 12 adapted to rest on a table, counter or the like. Within the receptacle 11 is an inclined bottom 14 terminating adjacent the lower edge of the front wall of the receptacle so as to provide a transverse slot for the reception of the vertical stationary member 15. A horizontal wall 16 is disposed beneath the inclined bottom 14 and between this wall and the bottom wall of the stand is arranged a spring 17 which normally

holds the receptacle 11 in elevated position. The member 15 is formed centrally with a vertical longitudinal slot 18 through which extends a pin 19 carried by the lower end of the front wall of the receptacle 11. The upper end of the receptacle carries a hinged lid 20, the forward edge of which abuts against the rear edge of a plate 21 secured across the upper end of the front wall of the receptacle. This plate 21 is formed with an elongated slot 22 extending approximately the entire width of the interior of the receptacle, this slot being the opening through which the matches are delivered, as will be more clearly set forth hereinafter. It will be noted that the front wall of the receptacle 11 slides between the front wall of the stand 10 and the member 15 thus guiding the member 15 vertically against the inner face of the front wall of the receptacle 11.

The upper end of the member 15 is formed with a groove 23 of such size and position as to comfortably hold a single match, and deep enough so that the match will not be jarred therefrom. In the upper portion of the front wall of the receptacle 11 is formed an opening 24, and in this opening is disposed a block 25 mounted on a horizontal pivot 26. A leaf spring 27 carried by the receptacle above the opening 24 bears with its free end against the upper portion of the block 25 and holds the same normally projected a slight distance into the receptacle. The upper edge of the block 25 is beveled as indicated at 28.

The member 15 has one of its upper corners cut away as indicated at 29 to receive a block 30 secured to the underside of the plate 21. The mutually adjacent vertical faces of both the block 30 and the wall of the cut away portion 29 are vertically grooved as shown at 31 and 32.

The normal position of the parts is shown clearly in Fig. 1, and when it is desired to operate the device to deliver a single match, the fingers of the hand are placed on the cover 20 and the receptacle 11 depressed. There will be one match in the groove of the member 15 and by reason of the crowding of the other matches in the receptacle, two or three other matches will lie on top of this first match. As the receptacle 11 moves downward the member 15 will ride up against the inner face of the front wall of the receptacle carrying the matches with it, but as the matches which are on top of

the one in the groove engage against the block 25 they will be pushed off and caused to fall down into the mass of matches in the receptacle. Further movement of the receptacle brings the block into engagement with the upper end of the member 15 which forces the block into the opening 24 against the tension of the spring. When the block has been pushed in, the block 30 engages the end of the match which projects over the cutaway portion 29 and tilts the end down into the cut away portion causing the match to swing upwardly through the slot 22 and stand in a vertical position. The end of the match within the receptacle will be disposed within the registered grooves 31 and 32. The match may then be readily removed, and the receptacle permitted to rise under the influence of the spring 17.

Particular attention is called to the fact that the block 25 is so positioned that the upper end of the member 15 will force it into the opening before the block can force the single match out of the groove. Particular attention is also invited to the block 30 which enters the cut away portion 29 so as to tilt the match and swing it into an upright position through the slot 22.

What is claimed is:

1. A single delivery match box including a stand, a resiliently held receptacle telescopically disposed for depression into the stand and provided with a delivery opening, means carried by the stand for supporting a match to a point of delivery, and means

carried by the depressible receptacle adjacent the delivery opening for knocking off superfluous matches from the carrier, whereby only a single match will be carried to the point of delivery.

2. In a single delivery match box, a magazine, a delivering slide movable through the magazine, and means carried by the magazine and normally arranged in position to engage and brush off the excess matches carried by the slide, and subsequently to be engaged and moved out of normal position by the slide.

3. In a single delivery match box, a magazine, a delivering slide movable through the magazine, and yieldably held means normally projecting into the path of the slide for brushing excess matches from the slide, said yieldable means being subsequently engaged and moved out of normal position by the slide.

4. In a single delivery match box, a magazine, a delivering slide movable through the magazine, and a resiliently held pivoted finger normally projecting into the path of the slide for brushing excess matches from the slide, said finger being subsequently engaged and moved out of normal position by the slide.

In testimony whereof, I affix my signature, in the presence of two witnesses.

WILLIAM PACHECO.
